MICHAEL FRIEDBERG, OF HARTFORD, CONNECTICUT

APPARATUS FOR STRETCHING TROUSERS

Application filed March 25, 1930. Serial No. 438,673.

This invention relates to apparatus that is designed to be used in tailoring establishments, particularly repair and pressing shops, in connection with a steam table.

- 5 The object of the invention is to provide a simple and easily manipulated apparatus by means of which trouser legs may be automatically stretched to exact lengths when placed over a steam table.
- 10 In attaining this end the apparatus has clamps for gripping the lower and upper ends of the trouser legs, and positive and yielding means for separating the clamps from each other and applying the required tension to the 15 trouser legs as they are subjected to the action of the steam table, with adjustable means for limiting the amount of stretch.

In the accompanying drawings Fig. 1 shows a plan of the apparatus in its contracted 20 condition. Fig. 2 is a plan of the same as when expanded. Fig. 3 is a side view of the apparatus expanded. Fig. 4 is a side view of the clamp for the lower ends of the legs. Fig. 5 is a section on the plane indicated by the 25 dotted line 5—5 on Fig. 1, of the clamp for the upper ends of the legs. Fig. 6 is a plan of one clamp member. Fig. 7 is a plan of the other clamp member.

The clamp for the lower ends of the trouser 30 legs comprises a bar 1 and a bar 2 that at one end are hinged together by a swivel bolt 3 and thumb nut 4, and at the other end are held together by a swivel bolt 5 and thumb nut 6. When the nut 6 is loosened, bolt 5 may be 35 swung out of the slot 7 and the bar 2 swung from the bar 1 on the bolt 3, for receiving the trouser legs. The adjacent faces of these bars are provided with material 12, as cork, which will grip the trousers without injury. 40 These clamp bars are adjustably fastened to a connecting bar 8 by means of a strap 9 secured to the clamp bar 1, and a thumb nut 10 on a screw that passes through the strap and a slot 11 in the connecting bar. When the nut 45 10 is loosened the clamp bars may be adjusted to any required position along the connecting bar.

The clamp for the upper ends of the trouser 50 legs comprises a bar 13 and a bar 14 which at one end are hinged together by a swivel bolt

15 and thumb nut 16, and at the other end are held by a swivel bolt 17 and thumb nut 18. When the nut 18 is loosened the bolt 17 may be swung out of the slot 19 and the bar 14 55 opened from the bar 13 for receiving the trouser legs. The inner faces of these clamp bars may be provided with cork inserts 12 to ensure a good grip.

The clamp bars 13 and 14 are fastened to the ends of a pair of connecting bars 20 that are spaced apart such a distance as will provide a sliding fit for the connecting bar 8 to which the other clamp bars are attached. Fastened to the ends of these connecting bars 20 is a strap 21 with ears 22 between which is pivoted the end of a lever 23, and fastened to the end of the connecting bar 8 is a strap 24 that has upwardly extending ears 25. The lever, at some distance from its pivot is provided with a pin 26 and connected between the ends of this pin and the ears 25 are a pair of springs 27. As the lever is pivoted to a part fastened to the connecting bars 20, and the ears 25 are fastened to the connecting bar 8, the springs tend to pull these bars so as to increase the distance between the clamps. 65 70 75

With the lever thrown over to the position shown in Fig. 1, so as to relieve the tension of the springs and allow the clamps to be drawn toward each other, the trousers are placed in the clamps. After the trousers have been clamped the lever is thrown over to the position shown in Figs. 2 and 3, which movement tensions the springs and causes them to move the clamps from each other and exert tension on the trousers. With the parts in this relation and clamping a pair of trousers, the whole is placed over a steam table and subjected to the action of steam which, softening the fibers of the material from which the trousers are made, causes them to stretch. 80 85 90

For the purpose of limiting the amount of stretch a stop 28 is adjustably fastened to the bar 8 by a thumb nut 29 on a screw 30 which passes through a slot 31 in the bar, which stop extends upward in position to engage the ends of a pin 32 that projects from the lever. The lever may be provided with a scale 33 for the purpose of setting the stop, 95 100

and thus limiting the stretch to the exact length. The springs, as the material of the trousers is softened by the steam, stretch the trousers until the pin engages the stop. After 5 they have been stretched to the required amount the trousers are taken and pressed.

The invention claimed is:

1. Apparatus for stretching trousers comprising clamps for gripping the ends of the 10 trouser legs, telescoping members connecting said clamps, a lever connected with one telescopic member, and spring means connected between the other telescopic member and said lever and tensioned to extend said telescopic 15 members and separate the clamps.
2. Apparatus for stretching trousers comprising clamps hinged at one end and detachably fastened at the other end for gripping the ends of the trouser legs, telescoping members 20 connecting said clamps, a lever connected with one telescopic member, and spring means connected between the other telescopic member and said lever and tensioned to extend said telescopic members and separate the 25 clamp.
3. Apparatus for stretching trousers comprising clamps for gripping the ends of the trouser legs, telescoping members connecting said clamps, a lever connected with one telescopic 30 member, spring means connected between the other telescopic member and said lever and tensioned to extend said telescopic members and separate the clamps, and an adjustable stop for limiting the separation of 35 the clamps.
4. Apparatus for stretching trousers comprising openable clamps with cork faces adapted to grip the ends of the trouser legs, telescoping members connecting said clamps, 40 a lever connected with one telescopic member and spring means connected between the other telescopic member and said lever.
5. Apparatus for stretching trousers comprising telescoping members, a clamp fastened to one telescopic member, a clamp adjustably attached to the other telescopic member, a lever connected with one telescopic member, and spring means connected between 45 said lever and the other telescopic member.
